Patented July 30, 1918.

FIG. 1.

FIG. 2.

FIG. 6.

FIG. 3.

Erwin Kramer,
Inventor

By his Attorney

R. R. Kilgore

UNITED STATES PATENT OFFICE.

ERWIN KRAMER, OF CARLSTADT, NEW JERSEY.

HOOK-AND-EYE TAPE.

1,274,283.

Specification of Letters Patent. Patented July 30, 1918.

Application filed March 22, 1917. Serial No. 156,711.

To all whom it may concern:

Be it known that I, ERWIN KRAMER, a citizen of the United States, residing at Carlstadt, in the county of Bergen and State 5 of New Jersey, have invented certain new and useful Improvements in Hook-and-Eye Tapes, of which the following is a specification.

My invention relates to hook and eye tapes 10 in which a laminated strip of fabric has a plurality of hooks or eyes secured between the layers with the operative parts exposed beyond one edge thereof and it is my object to produce a strong, simple, neat hook and 15 eye tape the manufacture of which will be free from all complications.

In the drawing Figure 1 is a face view 20 of my improved tape with the facing layer torn away at one end; Fig. 2 a back view with the base layer torn away at one end; and Fig. 3 a sectional view of the tape. Fig. 4 is an enlarged detail perspective view of the tape with the base strip flattened out and the facing strip turned up at right 25 angles thereto, to more clearly illustrate the manner of stitching, and also the location of the perforations in the line of stitching.

Fig. 5 is a cross sectional view on the line 5—5 of Fig. 4 showing how the stitching secures the facing and base fabrics together. 30

Fig. 6 is a view similar to Fig. 5 taken on the line 6—6 of Fig. 4 and showing how the stitching is confined wholly to the facing fabric at points where perforations occur 35 in the base.

Fig. 7 is a perspective view somewhat similar to Fig. 4 showing the facing fabric turned down, and illustrating the position of the perforations (in dotted lines) with 40 reference to the stitching.

Fig. 8 is a view of the tape after it has been folded along the line of stitching, and also showing how the fastener (in dotted lines) passes between the folded-back edge 45 of the base and the facing strip.

The improved hook and eye tape consists of a base fabric 1, and a facing fabric 2, one edge of the latter being secured to the former by a line of stitching 3 at a point 50 back from the edge of said base equal to the width of the facing strip, thus producing, even when the strip is in a flat condition as shown in Fig. 7, a continuous marginal pocket P for completely concealing 55 and protecting the anchor ends of the hooks and eyes as will presently appear. As shown

in the drawings, this base strip may be folded back upon itself along the line of the said stitching 3, merely for the purpose of facilitating the application of the tape strip 60 to a garment, since the stitching of the base and facing together as shown provides the necessary double-leaf housing for the anchor ends of the hooks.

At uniform intervals corresponding to 65 the hook and eye spacing a perforation or slit 4 is made in the base fabric in the line of the stitching 3, which perforation may be, and preferably is, made at the time of stitching by an intermittently operated perforating device on the sewing machine. This line of stitching 3 therefore passes through and secures the base and facing fabrics together except at the points where the base fabric has been perforated or slotted, thus 70 leaving openings in the base along the line of the said stitching 3 whereby the latter at these points is confined wholly to the facing fabric as shown on Fig. 6. The stitching 3 is therefore, straight ahead sewing and 75 the openings, properly spaced, are automatically provided for without the use of jump or tying stitches.

And, furthermore by locating these perforations or slits directly in the line of the 80 stitching 3, the latter imparts a substantial reinforcing effect to the tape at the points where the hooks or eyes are located thus enabling the same to withstand a maximum 85 pulling stress in the zone of each fastener. 90

The eyes 5 or hooks 6 are inserted in the marginal pocket P between one edge of the base strip 1 and the facing strip 2 with their shank portions projecting through the openings provided between the facing and base 95 at points where the slits 4 occur and across the line of the stitching 3 when the tape is in the flat condition shown in Fig. 7 or, when said tape is folded along the line of stitching as shown in Figs. 1, 2, and 3, the operative 100 portions of the hooks or eyes project beyond the edge of the tape. In its marketable form the tape is in the condition shown in Fig. 7 of the drawings but, as previously indicated, when it is desired to apply the same 105 to a garment it is folded along the line of stitching as clearly illustrated in Figs. 1, 2, and 3.

Figs. 4 to 8 inclusive of the drawings clearly illustrate the location of the perforations or slits 4 in the line of stitching 3. 110 Figs. 5 and 6 show how the stitching 3

unites the facing and base fabric at all points except where the perforations or slits 4 occur in the base which has the effect of providing an opening between the upper side 5 of the base and the lower side of the folded-in edge of the facing fabric, whereby when the fabric is folded along the line of stitching 3 as shown in Figs. 3 and 8, the shank of the fastener may project through the 10 opening thus formed and not through the perforation, while the raw edges of the said perforation or slit are exposed as clearly shown in enlarged form in Fig. 8.

This construction not only provides a very 15 reliable carrier for the hooks and eyes, but at the same time produces an exceptionally

strong and durable tape since the line of stitching is continuous and unbroken.

I claim:—

A hook or eye tape consisting of a base 20 fabric, a facing fabric, stitching securing the latter fabric to the former at a point back from the edge thereof to provide a continuous marginal pocket, and perforations formed in the base directly in the line of stitching. 25

In testimony whereof I have affixed my signature in the presence of two witnesses.

ERWIN KRAMER.
